US0D1016222S

(12) **United States Design Patent** (10) **Patent No.:** **US D1,016,222 S**
(45) **Date of Patent:** **** Feb. 27, 2024**

(54) **BASIN MIXER**

(71) Applicant: **Phoenix Industries Pty Ltd**, Bayswater (AU)

(72) Inventor: **Ban Hsi Liu**, Bayswater (AU)

(73) Assignee: **Phoenix Industries Pty Ltd**, Victoria (AU)

(**) Term: **15 Years**

(21) Appl. No.: **29/819,883**

(22) Filed: **Dec. 17, 2021**

(30) **Foreign Application Priority Data**

Jun. 29, 2021 (AU) 202113882
Jun. 29, 2021 (AU) 202113883
Jun. 29, 2021 (AU) 202113884
Jun. 29, 2021 (AU) 202113885
Jun. 29, 2021 (AU) 202113886
Jun. 29, 2021 (AU) 202113887

(51) **LOC (14) Cl.** **23-01**

(52) **U.S. Cl.**

USPC **D23/238**

(58) **Field of Classification Search**

USPC D23/238-244, 252, 254-255, 257, 499; D7/398
CPC F16K 31/602; F16K 31/605; F16K 31/607; E03C 1/0412

See application file for complete search history.

(57) **CLAIM**

The ornamental design for a basin mixer, as shown and described.

DESCRIPTION

FIG. 1 is an isometric front view of a basin mixer according to my new design;

FIG. 2 is an isometric rear view thereof;

FIG. 3 is a top view thereof;

FIG. 4 is a front view thereof;

FIG. 5 is a left side view thereof; and,

FIG. 6 is a right side view thereof.

1 Claim, 3 Drawing Sheets
